CAR COUPLING

Wade H. Hammond, Jr., Lillybrook, W. Va.

Application August 2, 1937, Serial No. 157,059

5 Claims. (Cl. 213—189)

My invention relates to improvements in car couplings and the primary object thereof is to provide an efficient coupling mechanism for use more particularly on mining cars and adapted to eliminate all hazards in the coupling of such cars thereby obviating injury to mine operatives particularly in underground work and on curves.

Another object is to provide a coupling for the purpose above set forth which is simple in construction, reliable in operation, inexpensive to manufacture and readily incorporated in the usual mine car without necessitating expensive modification of the latter.

To the accomplishment of the above and subordinate objects presently appearing, a preferred embodiment of my invention has been illustrated in the accompanying drawings, set forth in detail in the following description and defined in the claims appended hereto.

In said drawings:—

Figure 1 is a fragmentary view in top plan illustrating my improved coupling with the parts shown in coupling position,

Figure 2 is a similar view in side elevation,

Figure 3 is a view in longitudinal vertical section taken on the line 3—3 of Figure 1, looking in the direction indicated by the arrow,

Figure 4 is a view similar to Figure 3 illustrating the parts in uncoupling position,

Figure 5 is a view in transverse vertical section taken on the line 5—5 of Figure 4,

Figure 6 is a view in perspective of the coupling pin and a pin operating yoke,

Figure 7 is a view in perspective of a coupling bail,

Figure 8 is a similar view of a rock shaft and yoke operating arms thereon, and

Figure 9 is a fragmentary view in perspective of part of a rock bar for operating said arms and shaft.

Referring to the drawings by numerals, 1 and 2 designate the adjacent bumper ends of two mine cars, respectively, the construction of the remainder of which being well understood in the art has not been illustrated in the drawings.

According to my invention one of said ends, 1 in this instance, has mounted thereon a pair of upper and lower right angled plates 3 and 4 of heavy gauge metal spaced apart vertically and arranged to form a housing open at the sides and opposite the other end 2. The plates 3 and 4 are secured together in any suitable manner and to said end 1 as by bolts, a pair of which is shown at 5, said bolts passing through opposite sides of said plates 3 and 4 and through said end 1 and

surrounded by spacer sleeves 6 shown in dotted lines in Figure 1 disposed intermediate said plate. Centrally of the described housing contiguous to the open end thereof is a vertical king bolt 7 extending through said plates 3 and 4 and into the end 1. A draft or coupling link 8 is pivotally mounted adjacent one end thereof on said king bolt 7 intermediate the plates 3 and 4 so as to extend horizontally on one side of said bolt toward the other end 2 and for horizontal swinging movement. On the other side of the king bolt 7 the link 8 has an extension 9 to which is connected one end of a tension spring 10 the other end of which is connected, as at 11, to a fixed part of the housing so that said spring tensions said link against swinging movement. Pivotally mounted on the king bolt 7, on the top plate 4, is a crank 12 having a bifurcated end 13 straddling the link 8 whereby the latter may be swung from side to side by manipulation of the crank 12 for a purpose presently clear.

On the other end 2 is a similar pair of lower and upper right angled plates 14 and 15 secured to said end and to each other by any suitable means and designed to form a housing on said end 2 opposite the link 8 opening toward the end 1 and receiving therein the extended end of said link 8. The edges of the plates 14 and 15 opposed to the link 8 are inclined to form upper and lower flat cam ledges 16 and 17 facilitating entrance of the link 8 between the plates 14 and 15. At the sides of the plates 14 and 15 diverging webs, as at 18, connect said ledges 16 and 17 to further facilitate entrance of the link 8 between said plates 14 and 15.

Suitably secured to the top plate 15 is an open top casing like control box 19 centered on the housing formed by the plates 14 and 15 and including end walls 20, side walls 21 and a bottom wall 22. The elements 23 are space bars between the plate 15 and box 19 which need merely be identified in passing. Upstanding from the bottom wall 22 of the box 19 adjacent one end thereof and in the longitudinal center of said box is a tubular guide, or sleeve, 24 in which is vertically slidable a coupling pin 25. The coupling pin 25 is adapted to be elevated and lowered in said guide 24 in uncoupling and coupling positions respectively. In its coupling position said pin 25 extends through an aperture 26 in the bottom wall 22 of box 19 and similar apertures 27 and 28 in the plates 15 and 14 respectively. A socket 29 in the end 2 receives the lower end of said pin 25 in the coupling position thereof. As will be understood the coupling pin is designed to extend

55

through the coupling link 8 said link thereby forming a coupling member complementary to said pin. The guide 24 is braced at its top to the side walls 21 by a cross bar 30.

- 5 The coupling pin 25 is elevated and lowered through the medium of a vertically rocking and longitudinally sliding yoke 31 comprising a rod 32 extending loosely through said pin adjacent the upper end thereof and to project upon opposite 10 sides of the pin through a pair of diametrically opposed slots, one of which is shown at 33, provided in the guide 24. The rod 32 as will be understood plays up and down in the box 19. The remaining part of the yoke 31 is a U-shaped 15 yoke frame including a pair of side arms 33' extending from the rod 32 upon opposite sides of the guide 24, respectively, and slidably mounted intermediate their ends in a rock shaft 34 journalled horizontally in a bearing block 35 fast on 20 one side of said guide 24 substantially centrally thereof. Hooks 36 extend laterally from the arms 33' at the ends thereof opposite the rod 32 and similar hooks 37 from the ends of the rock shaft 34. A pair of yoke tensioning springs 38 connect 25 the hooks 37 and 38 on opposite sides of the described yoke frame. The arrangement of the described yoke 31 and springs 38 is such that when the coupling pin 25 is elevated or lowered in degree sufficient to move the yoke 31 past dead 30 center position relative to the axis of rotation thereof said yoke is slid longitudinally in the shaft 34 by the springs 38 and the coupling pin 25 moved to coupling or uncoupling position, as the case may be, under the tension of said springs 38. 35 The coupling and uncoupling positions of the pin 25 are established by coaction of the rod 32 with opposite ends of the described slots 33.
- The coupling pin 25 is initially moved toward coupling position by the following mechanism. 40 Journaled in suitable bearings 39, provided on the inner face of the sides 21 of box 19, and extending parallel with the rod 32 is a rock shaft 40 having extending therefrom a pair of yoke operating arms 41 overlying opposite ends of the rod 32. The shaft 40 and arms 41 are operative in one direction to depress said rod 32 and coupling pin 25 from uncoupling position. Beneath the rock shaft 40 and journalled in the sides 21 of box 19 for rocking movement is an arm operating 45 bar 42 provided with a pair of laterally extending hook-like members 43 overlying the arms 41, respectively, so that when said bar 42 is rocked in one direction said arms 41 will be depressed and the rod 32 and coupling pin 25 correspondingly moved. The bar 42 is rocked in said direction by means of crank arms 43 on opposite ends thereof depending from the bar on the outside of the box 19 and engaged by a rocking bail 44, comprising an upper cross rod 45 journalled in the 50 sides 21 of the box 19, parallel to the shaft 40, and above the same, a pair of side arms 46 depending from opposite end of said rod 45 upon opposite sides of said box 19 exteriorly thereof and an abutment bar 47 connecting the lower 55 ends of said arms 46 and swinging between the plates 14 and 15 behind the coupling pin 25. A tension spring 48 connected at one end, as at 49, to one end wall 20 of box 19 and at its other end to a bracket 50 on the cross bar 45, tensions the bail so that the abutment bar 47 is urged toward the coupling pin 25 or forwardly. Forward movement of said bar 47 is limited by the beforementioned webs 18. At this point it may be stated 60 that the guide arms 44 and crank arms 43 play

in slots 51 in the top plate 15 which extend laterally on both sides of the box 19 so that said arms and the abutment bar 47 are housed between the plates 14 and 15 to obviate danger from contact with these parts by mine operatives.

5

As a convenient and safe means for moving the coupling pin initially toward uncoupling position, a pair of U-shaped vertically swingable crank members 52 are journaled at their bends in opposite side walls 21 of the box 19 and in bearing 10 53 thereon with one arm 54 thereof inside said box and the other arm 55 thereof outside said box. The arm 54 of member 53 underlies opposite ends of the yoke rod 32 so that upward swinging of said members 52 elevates said rod 32 and the 15 coupling pin 25. A manually operative bail 56 is pivotally connected to the arm 55 of members 52. The bail 56, which may be termed an uncoupling bail, is of the proper size so that it may be swung upwardly on the members 52 over the box 19 for 20 operation by an attendant on the one car or swung into extended position relative to said members 52 toward the other car for operation by an attendant on said other car.

25

The operation of the invention will, it is believed, be understood from the foregoing. When it is desired to couple the cars together, the parts being in uncoupling position, the link 8 is swung by means of the crank 12 to center the same relative to the coupling pin 25. Upon movement of one car toward the other the link 8 abuts the abutment bar 47 swinging the same and the bail 44 rearwardly against the tension of the spring 48. The bar 47 engages the crank arms 43, rocks the bar 42 and depresses the yoke operating arms 41 as will be clear. The yoke rod 32 and coupling pin 25 are depressed until the yoke 31 is rocked past the described dead center position whereupon the yoke tensioning springs 38 complete movement of the coupling pin 25 to coupling position. The operation of moving the coupling pin 25 to uncoupling position will be understood from the foregoing without further explanation.

30

Manifestly changes in details of construction and arrangement of parts described in the foregoing may be resorted to without departing from the inventive concept disclosed and right is herein reserved to all such modifications falling within the scope of the claims appended hereto.

40

What I claim is:

1. A coupling mechanism for coupling two cars together comprising a link extended from one car for movement into coupling position by travel of said car toward the other, a coupling pin on the other car vertically movable in opposite directions into coupling and uncoupling positions, respectively, relative to said link, means for moving said pin comprising a tensioned yoke operatively connected to the pin and mounted for rocking movement in opposite directions past a dead center position relative to the axis of said pin to render the same effective, means for rocking said yoke in one direction past said position and operative by movement of said link against the same and manually operative means for rocking said yoke in the opposite direction past said position.

45

2. A coupling mechanism for coupling two cars together comprising a link extended from one car for movement into coupling position by travel of said car toward the other, a coupling pin on the other car vertically movable in opposite directions, respectively, into coupling and uncoupling positions relative to said link, means for

50

5 moving said pin comprising a tensioned yoke operatively connected to said pin and mounted for rocking movement in opposite directions past a dead center position relative to the axis of said pin to render the same effective, means for 10 rocking said yoke in one direction past said position comprising a swingably mounted bail operative by movement of said link against the same, means operative by said bail to impart movement to said yoke, and manually operative means 15 for rocking said yoke in the opposite direction past said position.

10 3. Coupling mechanism for coupling two cars together comprising a link extended from one car for movement into coupling position by travel of said car toward the other, a coupling pin on the other car vertically movable in coupling position relative to said link, means for moving said pin comprising a tensioned yoke operatively connected to said pin and mounted for rocking movement past a dead center position relative to the axis of said pin to render the same effective, and means for 20 rocking said yoke past said position comprising a swingably mounted bail operative by movement of said link against the same, a rock shaft 10 having crank ends thereon engaged by said bail with a wiping action to thereby impart movement to said shaft, a second rock shaft having bail operating arms extending therefrom, and operating connections between the first mentioned rock shaft and said bail operating arms comprising hooks extending from the first mentioned rock shaft and taking over said bail operating arms.

25 4. Coupling mechanism for coupling two cars together comprising a link extended from one car for movement into coupling position by travel 30 of said car toward the other, a coupling pin on the other car vertically movable in opposite directions into coupling and uncoupling positions, relative to said link, means for moving said pin comprising a tensioned yoke operatively connected to the pin and mounted for rocking movement in opposite directions past a dead center position relative to the axis of said pin to render the same effective, and means for 35 rocking said yoke in one direction past said position and operative by movement of said link against the same.

5 of said car toward the other, a coupling pin on the other car vertically movable into coupling position to said link, means for moving said pin comprising a tensioned yoke operatively connected to said pin and mounted for rocking movement past a dead center position relative to the axis of said pin to render the same effective, and means for 10 rocking said yoke past said position comprising a swingably mounted bail operative by movement of said link against the same, a rock shaft 10 having crank ends thereon engaged by said bail with a wiping action to thereby impart movement to said shaft, a second rock shaft having bail operating arms extending therefrom, and operating connections between the first mentioned rock shaft and said bail operating arms comprising hooks extending from the first mentioned rock shaft and taking over said bail operating arms.

15 5. A coupling mechanism for coupling two cars 20 together comprising a link extending from one car for movement into coupling position by travel of said car toward the other, a coupling pin on the other car vertically movable in opposite directions into coupling and uncoupling positions, 25 relative to said link, means for moving said pin comprising a tensioned yoke operatively connected to the pin and mounted for rocking movement in opposite directions past a dead center position relative to the axis of said pin to render 30 the same effective, and means for rocking said yoke in one direction past said position and operative by movement of said link against the same.

WADE H. HAMMOND, JR. 35
